UNITED STATES PATENT OFFICE.

FRANK T. PEARCE, OF PROVIDENCE, RHODE ISLAND.

DESIGN FOR A TRAY.

SPECIFICATION forming part of Design No. 22,685, dated August 8, 1893.

Application filed May 18, 1893. Serial No. 474,707. Term of patent 7 years.

To all whom it may concern:

Be it known that I, FRANK T. PEARCE, of Providence, in the county of Providence and State of Rhode Island, have invented and produced a new and original Design for Trays, of which the following is a specification, reference being had to the accompanying drawings forming part thereof.

Figure 1 represents a front view of a tray illustrating my new design. Fig. 2 represents a vertical sectional view of the same.

The leading features of my new design for trays consist in the general outlines of the raised edge together with the internal configurations.

In the drawings 5 indicates the raised edge, or rim, surrounding the central portion of the tray; this rim has the wide, curving upper end 6 and the narrow straight lower end 7, the

surface of the rim having the raised ornaments 8—8 and 9. The interior of the tray consists mainly of the raised portions 10 and 11 separated by the depression 12 with the depression 13 separating the lower edge of the raised portion 11 from the lower portion of the rim, the surface of the raised portion 11 being divided into a series of parallel concavities 14—14.

What I claim is—

The design for a tray, or similar article, as herein shown and described.

In witness whereof I have hereunto set my hand.

FRANK T. PEARCE.

Witnesses:

HENRY J. MILLER,
M. F. BLIGH.
